CLAIM

The ornamental design for a wireless antenna shroud, as shown and described.

DESCRIPTION

FIG. 1 is a front perspective view of the wireless antenna shroud showing our new design;

FIG. 2 is a back perspective view of the wireless antenna shroud;

FIG. 3 is a front elevational view of the wireless antenna shroud;

FIG. 4 is a back elevational view of the wireless antenna shroud;

FIG. 5 is a right side elevational view of the wireless antenna shroud;

FIG. 6 is a left side elevational view of the wireless antenna shroud;

FIG. 7, is a top elevational view of the wireless antenna shroud; and,

FIG. 8 is a bottom elevational view of the wireless antenna shroud.

The other broken lines in the Figures represent environmental subject matter only and form no part of the claimed design.

1 Claim, 5 Drawing Sheets
